UNITED STATES PATENT OFFICE

MATTHEW M. FRIEDEMANN, OF NEW YORK, N. Y.

DESIGN FOR A NOVELTY CONTAINER

Application filed February 16, 1932. Serial No. 42,886. Term of patent 14 years.

To all whom it may concern:

Be it known that I, MATTHEW M. FRIEDEMANN, a citizen of the United States, and a resident of New York, in the county and State of New York, have invented a new, original, and ornamental Design for a Novelty Container, as shown, of which the following is a specification, reference being had to the accompanying drawings, forming part hereof.

I claim:—

The ornamental design for a novely container as shown.

MATTHEW M. FRIEDEMANN.
